UNITED STATES PATENT OFFICE.

MARCUS O. ANTHONY, OF BAY CITY, ASSIGNOR OF ONE-HALF TO ISABELLA LANDSBERY, OF DETROIT, MICHIGAN.

SWING-BRIDGE.

SPECIFICATION forming part of Letters Patent No. 325,472, dated September 1, 1885.

Application filed October 22, 1884. (No model.)

To all whom it may concern:

Be it known that I, MARCUS O. ANTHONY, of Bay City, in the county of Bay and State of Michigan, have invented new and useful Improvements in Swing-Bridges; and I do hereby declare that the following is a full, clear, and exact description thereof, reference being had to the accompanying drawings, which form a part of this specification.

This invention relates to certain new and useful improvements in swing-bridges; and the invention consists in the peculiar arrangement and means employed for operating a gate so that such gate will bar the passages to the bridge when the same is opened to allow the passage of a vessel, and that will, when the bridge is closed, be depressed, all as more fully hereinafter set forth.

Figure 1 is a sectional side elevation. Fig. 2 is a plan with bridge partly opened. Fig. 3 is a vertical cross-section on the line *x x*, Fig. 2.

In the accompanying drawings, which form a part of this specification, A represents a swing-bridge, and B the stationary approach thereto, one being at each end of the bridge.

Underneath the floor of the bridge I secure in proper guides the rods C, the inner ends of which are pivotally secured to one end of the levers D, fulcrumed to the end of the bridge, and to the opposite ends of these levers I attach the outer ends of the rods E, which in turn are connected to the vertical lever F in such a manner that both systems of rods may be operated simultaneously. Upon the outer ends of the rods C are rigidly secured the curved rack-bars G.

H are other rods, secured in a like manner to the bed of the bridge, and which are also provided with a similar system of rods and levers connecting them to the lever I. The outer ends of the rods H are provided with heads J.

K is a shaft journaled in proper bearings underneath the roadway of the approach, one end projecting through the front wall of the approach, and has secured upon it a gear-wheel, L.

M is a gate-frame, the upper rail, N, of which forms one of the planks of the roadway when

the gate is in its depressed position, and to this rail N is attached one end of a chain or rope, O, the opposite end of which is secured to a drum, P, on the shaft K.

R are crossed rods or arms, the upper ends of which are pivoted to the vertical bars of the gate-frame, while their lower and opposite ends are pivotally secured to links S, which are in turn pivotally connected to the side foundation walls of the approach.

To the bottom rail of the gate frame I secure one end of the chains or ropes T, which pass up and over the pulleys U, and have secured to their free ends the weights V.

W is a dog or hook-latch pivotally secured in the bottom of the wall of the approach, and this dog is connected by a rod, X, to the inner end of the lever Y, the outer end of which projects through the front wall of the foundation in front of the gear-wheel L.

When the bridge is in position to allow travel over it, as in Fig. 1, the gate is depressed, with its top flush with the passages of the approach. If it is now desired to open the bridge, so as to allow of the passage of a vessel, the attendant, by means of the lever F, withdraws the rack-bars G from their engagement with the gear-wheels L. He then projects the rods H by means of the lever I. The heads of the rods impinging against the ends of the levers Y cause the dogs W to disengage from the bottom rail of the gate-frame, which is then free to be elevated vertically and laterally across the passages of the approach through the medium and gravity of the weights V, while springs *a b* respectively compel the rods H and lever Y to assume their original positions immediately upon the releasing of the lever I. The bridge is now free to be swung open, while the gate bars the approaches thereto.

When the gate is to be closed, the operator projects the racks G by means of the lever F, and then swings the bridge in either direction, the rack-bars engaging with the gear-wheels G, rotating the same, and by the connections named winds the chain O upon the drum P, thereby drawing down the gate to its original position, the bottom rail of the gate engaging with the dog W, which locks it to such posi-

tion until released by repeating the operation hereinbefore described.

What I claim as my invention is—

1. A swing-bridge having secured at either end a projecting and retracting rack adapted to engage with a pinion, thereby giving a vertical motion to a gate adapted to project from the floor of the stationary part of the bridge, substantially as described.
- 10 2. In combination with a swing-bridge, a detent for holding the gate down and a lever for disengaging such detent, such lever being operated from the center of the swing-bridge, substantially as and for the purposes specified.
- 15 3. In combination with a swing-bridge, a gate at each end thereof, a detent for holding down each gate, and a lever operated from the bridge for disengaging said detents simultaneously, substantially as and for the purposes specified.
- 20 4. In combination with a swing-bridge, and as a means for operating the gate in the stationary part thereof, a rack-bar conforming in shape to the end of such swing-bridge, and secured beneath the floor of the same at its end, and adapted to be projected or retracted by means of a lever at the center of such swing-bridge, substantially as described.
- 25 5. In combination with a swing-bridge, a gate, a detent for holding said gate down, a lever and intermediate connections for disengaging said detent, and a weight attached to said gate for elevating the same when said detent is disengaged, substantially as described.
- 30 6. In combination with a swing-bridge, and as means for operating the gate in the stationary part thereof, the shaft K, gear-wheel L, carried by said shaft, rod C, the curved rack-bar G, secured to said rod, and the lever F, arranged at the center of said bridge and 40 constructed to project and retract said rack-bar, substantially as and for the purposes specified.
- 35 7. In combination with a swing-bridge, the gate-frame M, shaft K, drum P, carried by 45 said shaft, the crossed arms R, links S, pivotally secured to said arms and to the side walls of the approach, the rope O, chain T, and weight U, all constructed and arranged substantially as and for the purposes specified. 50

MARCUS O. ANTHONY.
